RUDOLPH MILECZ, OF HOBOKEN, NEW JERSEY.

SOUND REPRODUCTION.

Application filed October 31, 1925. Serial No. 65,972.

This invention relates to a method of reproducing sound and to apparatus for practicing the same.

The primary object of this invention is to 5 reproduce faithfully original sounds that have been translated into energy, either mechanical or electrical. A special object is to produce an instrument capable of accurately responding to all the notes of the musical 10 scale and of recreating the tonal characteristics of any voice or instrument. The system disclosed is based on the laws of dynamics, particularly on that law relating to the action of a force against mass.

15 The sensation called sound results from a succession of impulses reaching the ear. If a sound could be dissected, each impulse, heard alone, would be audible as a tap or knock. The louder the individual taps, the greater the 20 volume of the resulting sound; while the more distinct the taps, the clearer the quality of the sound. To produce taps having the desired qualities we must create impulses having corresponding properties.

25 The ideal way to produce a series of separate, distinct sound impulses is by a succession of equal hammer blows upon a non-vibratory member. Each blow will produce a single primary impulse, and since the member does not vibrate there will be no secondary 30 impulses to confuse the orderly procession of primary impulses. There will result a series of separate, staccato impulses of equal intensity that will be heard as a clear, pure tone.

35 A vibrating member will produce a series of impulses, but they will be of a legato, muffled, run-together character, since the vibrating member merely moves to and fro under constant restraint. The resultant tone will 40 therefore be muffled and run-together. This defect is inherent in any system producing impulses by vibrating a member, such as a diaphragm, and the resulting imperfect tone is further distorted by the use of an amplifying horn, since the latter has tonal characteristics of its own which must unavoidably 45 have some effect upon the sound passing through it.

The present invention avoids these faults 50 of the known systems of sound reproduction by utilizing a series of hammer blows, as outlined above. An "audifier" having a natural period of vibration far below the frequencies of the musical scale is used to translate the 55 blows into impulses which are interpreted by the ear as sound. Suitable mechanism, op-

erated either electromagnetically or mechanically, provides a "hammering instrument" for imparting blows to the "audifier".

Other features of the invention will become apparent in the following description, in which I have disclosed preferred embodiments by way of illustration.

In the drawings:

Fig. 1 is a side elevation of an electro-magnetically operated reproducer with only the base portion of the "audifier" shown.

Fig. 2 is a plan view of the reproducer on the plane of line 2—2 of Fig. 1.

Fig. 3 is a cross section on the line 3—3 of Fig. 2.

Fig. 4 is a detached view of the "audifier".

Fig. 5 is an enlarged plan view of the transmitting tip.

Fig. 6 is a cross sectional view of the same taken on the line 6—6 of Fig. 5.

Fig. 7 is a side elevation of a mechanically operated reproducer.

Fig. 8 is a cross sectional view through the rotating table of the mechanically operated reproducer showing certain modifications.

Fig. 9 is a plan view of the clamp shown in Fig. 8.

Fig. 10 is a diagrammatic view showing the flexure of the "audifier".

Fig. 11 is a diagrammatic view illustrating the principle of mass interaction.

The "audifier", as shown in Fig. 4, is a bell-shaped member having a tubular neck 23 connected to a flat rim 25 by flaring side walls 24. The transmitting tip 19 secured in the end of the tubular neck is adapted to receive the blows of the "hammering instrument". The side walls 24 are curved on substantially the arc of a circle, allowing the "audifier" to flex under the force of a blow to the position indicated in an exaggerated way by the dotted lines in Fig. 10. The curvature must be extended far enough to give the required flexibility but not so far as to produce tension due to the overhanging weight of the rim. A curvature of about 110° of a circle, as shown in Fig. 10, has been found satisfactory.

Several factors must be considered in selecting the material for the "audifier". The construction must be such that when tip 19 receives a blow the "audifier" does not audibly vibrate, but sends forth a single sound impulse which is heard as a dull tap far below the range of the musical scale. The material must be sufficiently elastic to permit

the walls to flex as shown in Fig. 10, and must also have the quality of returning rapidly to its normal relaxed condition, since every single blow must meet the resonator in its relaxed state. It has been found that the lighter the specific gravity of a substance, the more rapidly it returns to its relaxed state. Tests have shown that paper, stiffened felt, or a substance having a similar specific gravity, meet the requirements.

The transmitting tip, shown in Figs. 5 and 6, must be rigid, so it can transmit the full force of the blow to the "audifier", and must also be of light weight, as a heavy mass would absorb part of the energy of the blow. The tip is accordingly made of aluminum or similar light metal and is perforated at 21 to further reduce the weight. An upstanding flange 22 is provided for attaching the tip to the "audifier".

In the mechanically operated reproducer, shown in Fig. 7, the blows are imparted to the transmitting tip by the "hills" of a vertically cut phonographic record 38. The turn-table 42, which is rotated by any well-known means, is slightly "dished" in the center, as shown at 46 (Fig. 8), and a rubber pad 45 is interposed between the turn-table and the record. As a result of this structure, when nut 41 is tightened, the record is rigidly clamped to the turn-table, and for the purposes of this invention is practically integral therewith.

The transmitting tip is provided with a jeweled point 20 (Fig. 6), adapted to cooperate with the groove of the record. The "audifier" is held in position by clamping the transmitting tip in the end of a lever 28 of wood or similar light material. The opposite end of lever 28 is pivoted in a yoke 31, which latter is rigidly attached to a second yoke 39. The yoke 39 is free to swivel about post 40, but is supported vertically by having a screw-threaded connection with the post. This construction supports the "audifier" in an upright position with the transmitting tip free to swing laterally to follow the groove, with the "audifier" free to move vertically, and with the bell portion of the "audifier" free and unconfined.

When the machine is operated, turn-table 42 rotates and each "hill" in the record groove imparts a blow to the transmitting tip. The "audifier" is free to move vertically, so that after each blow its momentum carries it free of the "hill", and then, due to its weight, it falls back to meet the next blow. If the "audifier" were a rigid member, its "range of displacement", (the distance momentum carries it from the "hill"), would be so great that it could not fall back in time to meet the next "hill". But the side walls of the "audifier" are flexible, as pointed out above, and part of the force of the blow is used in distorting the "audifier", as shown in

Fig. 10. The distortion puts the walls under a stress and calls forth the force tending to restore the walls to their normal relaxed state. This latter force may appropriately be called the "force of restitution". It may be said, then, that the flexibility of the side walls makes the reaction of the "audifier" more rapid (1) by reducing the range of displacement, since it absorbs part of the force of the blow, (2) by making possible the "force of restitution", which adds its force to that of gravity in returning the transmitting tip to meet the next blow.

Since each blow on the "audifier" is a collision between two masses, we must consider the laws of dynamics in designing the masses to insure a proper rebound of the "audifier" after every impact. Considering Fig. 11, if pivoted lever 47, which has a weight of one unit, be raised and allowed to fall against the mass 48, which has a weight of 50 units, the lever will rebound sharply while the mass will be unaffected, due to its inertia. If the lever and mass were of the same weight, they would react equally.

In the sound reproducer of this invention it would be undesirable to allow the turn-table to react after each impact, since such reaction would produce detrimental vibration of the turn-table, and would absorb part of the energy of the blow, preventing the full intensity of the impact from being transmitted to the "audifier". The turn-table is therefore given sufficient inertia to render it indifferent to the impact by giving it a mass at least fifty times that of the "audifier".

In the machine shown in Fig. 7, the transmitting tip rests directly upon the record. A modified mounting is shown in Fig. 8, in which rubber sleeves 51 and 52 are inserted in the upper and lower ends, respectively, of a bore 50 formed in the end of arm 28. The transmitting tip 19 is mounted in the upper sleeve, while a stud 53 carrying the diamond point 54 is inserted in the lower sleeve. This form of mounting reduces the intensity of the blows transmitted to the "audifier" and hence diminishes the loudness, but at the same time gives softer tones and eliminates surface noises.

A modified form of clamp is also shown in Fig. 8. The clamp 43 is provided with a slot 49 so that it may be readily inserted under the thumbscrew 44, thus providing a rapid and efficient clamp.

In the form of the invention illustrated in Figs. 1 to 3, the "hammering instrument" is operated electromagnetically. An electromagnet 12 is yieldingly supported on the base 10 by means of a spring 13 and adjustable screw 14. Cooperating with the magnet is an armature in the form of a reed 15 which is formed integrally with the block 15^a, the block being clamped by a screw 17 to a massive pedestal 16 rising from the base. The

"audifier" is supported in free gravitational suspension with the transmitting tip in contact with the reed by securing the transmitting tip in a split clamp 27 on one end of the 5 arm 28 of wood or other light material. The opposite end of arm 28 is held between nuts 29 on a screw rod 30 swiveled in the arms 31 of a yoke 32 which is adjustably supported by a screw 33 on a relatively massive post 34 10 extending up from the base. Terminals for the electromagnet are indicated at 36, 37.

In this modification the reed 15 is caused to vibrate by passing an interrupted current, whose pulsations correspond to the desired 15 sound, through the electromagnet. The vibrations of the reed 15 are imparted to the "audifier" as a series of blows. It is the free gravitational suspension of the "audifier", together with its flexibility, that enable it to react in such a manner as to receive a clean 20 impact from each upward stroke of the reed.

The reed is designed with a natural period of vibration of about 7000 vibrations per second, so as to be capable of transmitting all 25 notes of the musical scale without distortion.

The "audifier" will respond properly to only a certain "range of displacement". If the range is too great, the "force of restitution" is ineffective; while if too small, the 30 reed does not gain enough mechanical advantage to impart a sharp blow. The reed has a greater amplitude of vibration at its free end than toward its confined end, and hence by moving the transmitting tip along 35 the length of the reed, a critical point or focus can be found at which the "audifier" is given the optimum "range of displacement". Once this focus is located the screw 33 is tightened and the instrument is permanently 40 set.

The machine of Fig. 1 normally rests on feet 55 and 56, but may be turned on its side and stood on feet 57 and 58. In either position the "audifier" is suspended in free gravitational 45 relation.

The reed 15 is a very stiff member and hence it is necessary to support it on a heavy mass that will not be affected by vibration of the reed so that the full force of the blows will 50 be transmitted to the "audifier". The base 10 should therefore have a mass at least fifty times as great as that of the "audifier".

Since the vibrations of the reed correspond to the vibrations of the original sound waves 55 as carried by the electric current, it is possible to use the reed to cut a master phonograph record. This can be done by removing the "audifier" and mounting a cutting point on the reed. The blank record is then rotated by any suitable means, as by a turning lathe, while the vibrating reed is progressively moved across its face by any suitable feed mechanism.

It should be noted that the "audifier" is 60 in no sense a horn, and is given its bell-

shaped form merely to give it the proper flexibility. This shape also enables it to be supported in an upright position without putting any part of its walls under tension, and helps to absorb all the energy of the blow 70 in a single pulsation of deformation and restitution. While the "auditor" is shown as tubular, it could obviously be made hexagonal, square, or any equivalent shape. 75

The walls of the "audifier" can be made of any thickness within reasonable limits, since increasing the thickness reduces flexibility, and hence reduces the force of restitution, but at the same time increases the weight, thereby increasing the effect of gravity and compensating for the diminished force of restitution. 80

As stated before, a louder sound results from louder individual taps. Louder taps can be produced by using a larger "audifier", 85 which will be heavier and hence cause more vehement impacts. Since this system is based on the laws of dynamics, the size of the "audifier" can be mathematically calculated to produce any desired volume of sound. 90

Summarizing, we can say that this system of sound reproduction is based on the interaction of masses induced by imparting a succession of blows to an "audifier". It is the free gravitational suspension of the "audifier", 95 together with its bell-like form giving it the proper flexibility, that enable the "audifier" to react so as to receive a clean impact from each blow at any frequency within the musical scale. 100

What I claim is:—

1. A sound reproducer comprising a sounding instrument having a tip secured thereto, a reed, said sounding instrument resting on said reed in free gravitational relation, and electromagnetic means for vibrating said reed. 105

2. A sound reproducer comprising a sounding instrument having a neck portion and a bell portion, a transmitting tip carried by the neck portion, and a vibrating reed mounted to impart a series of blows to said tip. 110

3. A sound reproducer comprising a sounding instrument having a neck portion and an outwardly flaring bell portion, a transmitting tip carried by the neck portion, a pivoted lever engaged with said tip and supporting the sounding instrument with its bell portion in free, unrestrained relation, and electromagnetic means for imparting a series of impacts to said tip. 115

4. A sound reproducer comprising a sounding instrument having a tip secured thereto, a pivoted lever carrying said tip, said lever being adjustably mounted upon a base, a reed mounted on said base in operative relation to said tip, and means for vibrating said reed. 120

5. A sound reproducer comprising a sounding instrument having a neck portion and a bell portion, a transmitting tip carried by the 130

- neck portion, a pivoted lever engaged with said tip and supporting the sounding instrument with its bell portion in free, unrestrained relation, a base upon which said lever is adjustably mounted, a reed mounted on said base, said tip resting in free gravitational relation against said reed, and electromagnetic means for vibrating said reed.
6. A sound instrument comprising a reed having a natural period of vibration higher than the frequencies of the musical scale, a base supporting said reed, and electromagnetic means for vibrating said reed.
7. A sound instrument comprising a reed having a natural period of vibration higher

than the frequencies of the musical scale, a relatively massive base supporting said reed, and electromagnetic means for vibrating said reed.

8. Sounding mechanism comprising a support, a tongue connected to the support at its root, a contact tip adapted to engage one side of the free end of the tongue, said tip being disjunct from the tongue, electromagnetic means engaging the other side of the tongue for agitating the tongue, and a flexible reactive member connected to the tip.

In testimony whereof I affix my signature,

RUDOLPH MILECZ.
